UNITED STATES PATENT OFFICE.

CHARLES J. BURTON, OF BEATRICE, NEBRASKA.

BOOTH.

No. 895,538.

Specification of Letters Patent.

Patented Aug. 11, 1908.

Application filed May 23, 1907. Serial No. 375,256.

To all whom it may concern:

Be it known that I, CHARLES J. BURTON, a citizen of the United States, residing at Beatrice, in the county of Gage and State of Nebraska, have invented a new and useful Booth, of which the following is a specification.

This invention relates to folding booths for voting and analogous purposes.

10 The primary object of the present invention is to provide a simple structure of a novel nature, that can be compactly folded, so that it will occupy but very little space, and can be easily transported and which 15 when set up, constitutes an effective and completely inclosed booth within which a voter may prepare his ballot in complete secrecy.

The preferred embodiment of the invention is illustrated in the accompanying drawings, wherein:—

Figure 1 is a perspective view of a double booth with the curtain removed from one of the inclosures. Fig. 2 is a vertical sectional view therethrough. Fig. 3 is a detail horizontal sectional view on the line 3—3 of Fig. 2. Fig. 4 is a detail sectional view on the line 4—4 of Fig. 3. Fig. 5 is a detail sectional view on the line 5—5 of Fig. 2. Fig. 30 6 is a detail sectional view showing the locking device for the base.

Similar reference numerals designate corresponding parts in all the figures of the drawings.

35 In the embodiment illustrated, spaced standards 7 are employed, preferably constructed of angle metal and connected by arms 8 that comprise hingedly connected links 9 that are pivotally connected to the 40 standards. Two of these arms are employed, and between them are located crossed braces 10, each brace being pivoted to one of the standards, as shown at 11 and having a headed stud 12 at its other end that 45 detachably engages in a key-hole slot 13 formed in the other standard. These braces serve to prevent the folding of the arms 8, and thus maintain the standard 7 in separated condition, and in parallel relation. The 50 standards are maintained in upright positions by a base consisting of oppositely disposed sleepers 14 pivotally connected as shown at 15 to the lower end of each standard. The sleepers may be secured if desired 55 to a floor by fasteners 14^a passed through angle brackets 15^a secured to said sleepers.

Braces 16, pivoted to the sleepers, have studs 17 at their upper ends that detachably engage in key-hole slots 18 formed in the standards, said braces thus maintaining the 60 sleepers at right angles to the standards. In order to prevent accidental detachment of the headed studs 17 from their sockets 18, keeper hooks 19, pivoted by rivets 20 or other suitable devices to the standards have 65 notches 21 that receive the studs, said hooks engaging between the braces and standards, as shown in Fig. 1, and being preferably provided with outstanding operating lips 22.

Shelf supporting arms 23 of angle metal 70 are pivoted at 24 to the standards and have horizontal flanges 25 and upright flanges 26. Shelves, preferably constructed of hingedly connected sections 27, have their ends resting upon the horizontal flanges 25, and between the upright flanges 26, these shelves carrying hooks 28 that detachably engage over the upright flanges.

Curtain or wall supporting arms 29 are 75 pivotally connected, as shown at 30 to the upper ends of the standards, and are disposed in horizontal position when the frame is set up. They are provided contiguous to their pivoted ends and in their upper edges with notches 31. Upper and lower braces 80 32 and 33 are pivoted to the standards between the arms 23 and 29 by common rivets or other devices 34. The upper braces 32 have key-hole sockets 35 in their free ends that receive headed studs 36 projecting from 85 the outer sides of the arms 29 between the ends thereof, the lower arms 33 being provided in their ends with key-holes sockets 37 that in like manner receive outstanding headed studs 38 carried by the outer ends of 90 the shelf supporting arms 23. It will thus be seen that the shelf supporting arms and curtain or wall supporting arms will be maintained in horizontal position by the 95 braces.

For each booth, a curtain 39 is employed, which extends across the space between the standards, and has openings 40 in its upper margin, through which pass the arms 29. The curtains rest in the notches 31 and extend along and outside said arms 29. They are provided with sockets 41 that receive the outer ends of the arms beyond the braces 30, and said braces as well as the braces 33 are located outside the curtain, as shown in 105 Fig. 1. Openings are therefore formed in the curtain to permit the passage there-

through of the studs 36 and 38. The upright edges of the curtain preferably meet at one of the outer corners of the booth and these edges are secured together by a hook 5 and eye 42 located at the upper corners.

It will be evident that this structure when set up constitutes an effective booth that entirely conceals the upper portion of a person located therein and permits him to pare a ballot with the utmost secrecy. At the same time, the structure can be readily and compactly folded so that it will occupy but very little space, and can be easily transported. It will be evident that any number 10 of booths may be employed, as desired. While a double booth is shown, a single booth may be constructed by leaving off the mechanism on one side of the standards. Moreover the structure can be secured to a 15 wall or other support.

From the foregoing, it is thought that the construction, operation, and many advantages of the herein described invention will be apparent to those skilled in the art, without further description, and it will be understood that various changes in the size, shape, proportion, and minor details of construction, may be resorted to without departing from the spirit or sacrificing any of the advantages 20 of the invention.

Having thus fully described my invention, what I claim as new, and desire to secure by Letters Patent, is:—

1. The combination with a standard member, of a sleeper member pivoted to the lower end thereof, a brace pivoted to one member and having a headed stud, the other member having a key-hole socket that detachably receives the headed stud, and a keeper movably mounted on the latter member and detachably engaging the stud to maintain it in the smaller portion of the key-hole socket.

2. The combination with a standard member, of a sleeper member pivoted to the lower end thereof, a brace pivoted to one member and having a stud, the other member having a socket that detachably receives the stud, and a keeper having a portion that fits between said member and the brace and detachably engages the stud to hold it against movement in the socket.

3. The combination with a standard member, of a plurality of sleeper members pivoted thereto, a plurality of braces connected to the sleeper members and detachably interlocked with the standard members, and a device mounted on the standard members and detachably engaging with the different 50 braces to maintain their interlocking engagements with the standard member.

4. The combination with a standard member having a plurality of sockets, of a plurality of sleeper members pivoted to the 55 standard member, braces of different lengths

pivoted respectively to the sleeper members and having studs that detachably engage in the sockets, and a hook pivoted on the standard member and having notches that receive the studs.

5. The combination with standards, of foldable connections between the standards, shelf supporting arms mounted on the standards, and a shelf mounted on and interlocked with the shelf supporting arms to maintain 70 them in separated positions.

6. The combination with standards comprising angle bars, of sleepers pivoted to the outer flanges of the bars, holding means for the sleepers engaged with said outer flanges, 80 foldable connections between the standards connected to the inner flanges thereof, shelf supporting arms pivotally mounted on the outer flanges, and a shelf detachably mounted on the arms and having a portion located between the same to prevent the relative movement of the arms towards each other.

7. In a folding booth, the combination with a shelf supporting arm of angle metal, of a shelf that rests on one of the flanges of said arm, and a hook carried by the shelf and detachably engaging over the other flange.

8. In a folding booth, the combination with spaced shelf supporting arms of angle metal, of a shelf comprising hingedly connected sections that rest upon the horizontal flanges of the arms and between the upright flanges thereof, and hooks carried by the ends of the shelf and detachably engaging over the upright flanges.

9. In a folding booth, the combination with spaced supporting standards, of curtain supporting arms outstanding therefrom, braces connecting the standards and arms and having detachable stud connections with the latter, a curtain extending across the space between the standards and having openings that receive said arms, said curtain extending between the braces and arms outside the latter and having openings to receive the stud connections thereof, said curtain furthermore having sockets that receive the outer ends of the arms, and means for securing the upright margins of the curtain together.

10. In a folding booth, the combination with a standard, of a shelf supporting arm pivoted to the standard, a wall supporting arm also pivoted to the standard above the shelf supporting arm, and a plurality of braces having a single intermediate pivotal connection with said standard between the pivots of the arms, a detachable connection between one of the braces and one of the arms, and a detachable connection between the other brace and the other arm, said braces and arms when detached being foldable alongside the standard and when connected being held against pivotal movement.

11. In a folding booth, the combination 130

with spaced standards, of shelf supporting arms pivoted thereto and comprising angle metal having horizontal and upright flanges, a shelf having its ends resting on the horizontal flanges and located between the upright flanges, a curtain bridging the space between the standards and having openings that receive the shelf supporting arms, said curtain extending outside said arms, and 5 braces pivoted to the standards and located outside the curtain, said braces having stud connections with the outer ends of the shelf supporting arms which connections pass through the curtain.

10 12. In a folding booth, the combination with spaced standards, of foldable connections between the standards, upper curtain supporting arms pivoted to the upper ends of the standards, lower shelf supporting arms 15 pivoted to the standards, a curtain extending 20

across the space between the standards and having openings through which the arms extend, said curtain being located along and outside the arms, a shelf supported on the lower arms within the curtain, braces pivoted 25 to the standards outside the curtain, and detachable connections between the free ends of the braces and the upper and lower arms, said connections passing through the curtain, the curtain having interlocking engagements 30 with the outer ends of the curtain supporting arms.

In testimony, that I claim the foregoing as my own, I have hereto affixed my signature in the presence of two witnesses.

CHARLES J. BURTON.
